ABSTRACT

A gas supply plant particularly for use in supplying an insulating gaseous medium such as SF₆ to a switching installation insulated with the gas includes a storage container receiving the gas in a pressurized state from a compressor drawing gas from the low pressure side of the switching installation and adapted to deliver the gas to the high pressure side of the switching installation. A heated ancillary pressurized gas container for supplying make-up gas is connected to the storage container by a pipe line containing a control valve and operation of this valve is controlled by conjointly acting signals derived respectively from the pressure of the medium within the storage container and its state.

APPARATUS FOR MONITORING THE FILLING FACTOR OF CONTAINERS FOR COMPRESSED GAS

The present invention relates to a device for monitoring the extent to which gas containers are filled, especially storage containers for SF₆ for use in electrical switch devices insulated with this gas and for regulating the inflow of SF₆ gas from an adjoining heated SF₆ gas cylinder with a pressure gauge for monitoring the pressure in the storage cylinder.

In gas supply installations of an encapsulated SF₆ plant, because of the fact that the power switch must be ready for re-operation in a very short time after one switching operation has been carried out, it is necessary to install a storage container which also serves at the same time as a buffer container into which it is possible for a compressor to pump the gas and which can draw the gas from the low-pressure section of the switch. In such installation, losses by leakage are unavoidable so that after a certain time it is necessary for the storage container to be topped up once again. Furthermore, it is also possible for losses of gas to occur as a result of misswitching in the gas supply lines. These losses of gas then show themselves in the form of a reduction in pressure in the storage container.

SF₆ has the property of liquefying at a given pressure and at a temperature such as can occur in particular in open air installations.

As a result of such a liquefaction, the pressure falls considerably; by a contact pressure gauge a control order is transmitted to a solenoid valve to the effect that a further quantity of SF₆ should be fed from a storage cylinder to make up for the leakage losses.

However, the problem consists in the fact that the further quantity of SF₆ fed in liquefies because of the low temperature, so that one cannot measure SF sufficient rise in pressure. In the most unfavorable instance, the storage container can be completely filled with liquid SF₆. In order to avoid this, it is necessary to measure not only the pressure but also the temperature; the operator reads from the *p-t* graph for SF₆ gas the maximum pressure which occurs at a given temperature and at which no liquefaction as yet takes place.

However, in order to avoid such an expenditure of labor, it has been proposed that the storage container should be surrounded by a heating winding and that the SF₆ should be maintained at an adequately high temperature. However, such a heating winding is troublesome and expensive.

The problem underlying the invention is that of providing a device of the type mentioned above, in which a heating winding is no longer required and which automatically controls a solenoid valve for topping up with SF₆ depending both on the pressure in the storage vessel and also on the liquid level. It is particularly desirable, if the ambient temperature is very low, to avoid a further unnecessary topping up which can lead to even more liquid SF₆.

This problem is solved with a device of the type mentioned above in that a measuring unit is provided at the lowest position in the storage container which responds to the change in the physical condition, and which acts on the adjusting member in the sense of a superimposition of the pressure gauge.

In this case the measuring member is advantageously a hot conductor which is provided in one branch of a bridge circuit.

In a further form of embodiment, the measuring member used is a plate condenser which is provided in one branch of a capacitance measuring bridge. Instead of a circuit arrangement with a hot conductor or a condenser it is also possible to provide a known float which, when a given quantity of liquid or a given level of liquid is reached in the container, actuates a contact whose output signal can be switched to an AND member for linking with the measuring impulses of the pressure gauge.

The advantage of the device according to the invention consists in the fact that on the one hand a heating device no longer has to be provided, and that furthermore additional measurements, especially the determination of the critical pressure and of the critical temperature or of the liquefaction pressure and the liquefaction temperature no longer have to be carried out separately.

A preferred embodiment of the invention will now be explained in detail on the basis of the accompanying drawing wherein:

25 FIG. 1 is a diagrammatic view of the improved SF₆ supply system;

FIG. 2 is a detail showing the hot conductor inserted in a blind hole of the SF₆ container; and

30 FIG. 3 illustrates a modification of the circuit shown in FIG. 1 wherein a capacitance bridge is utilized in lieu of a resistance bridge.

With reference now to FIG. 1, a storage vessel 1 for a switching installation insulated with SF₆, not illustrated, receives the SF₆ gas during normal operation 35 through a pipe 2 coming from a compressor 3, which draws switch-arc contaminated SF₆ via pipe 24 from the low-pressure space 23 of a switching installation not represented in greater detail and pumps it into the container 1. The contaminated SF₆ gas is purified by a filter 4. In order to top up the container 1 in the event of a loss through leakage there is provided a further heated container 5 which is installed as a storage cylinder. This container 5 is connected via a pipe 6 with the storage container 1; in addition there is provided a solenoid valve 7 which opens up the pipe 6 from the container 5 to the container 1 in the event of a leakage loss. From container 1, the re-compressed and filtered gas is led back via pipe 25 to the high-pressure space 28 of the switching installation.

50 Monitoring of the container in accordance with the illustrated embodiment of the invention takes place by means which include a contact pressure gauge 8 and a bridge circuit 9. This bridge circuit 9 includes four resistances, one of which, resistance 10, the one located

55 on the container, is designed as a hot conductor, whilst the other three, 11, 12, 13, are normal resistances. One diagonal of this bridge is fed by means of a source of alternating voltage 14, whilst the drop in potential on the other diagonal, that is to say at the junction of resistances 10, 11 and resistances 12, 13, is fed to an amplifier unit 15, the output of which energizes the actuating magnet 16 of a relay 17. Relay 17 and another relay

60 19 together form an AND member, the output signal of which controls the solenoid valve 7. That is to say, solenoid valve 7 is energized and opened to connect the storage cylinder 5 with container 1 only when both relays 17 and 19 are actuated.

If the pressure in the storage container 1 now becomes too low, the contact pressure gauge 8 responds, and its output signal energizes via conductor 26 the actuating magnet 18 of a second relay 19 connected in series with relay 17 via conductor 33. If now at the same time there is a quantity of liquid inside the container, then the relay 17 attracts and opens. Thus while the relay contact 19 is indeed closed, relay 17 is open with the result that no current can flow through the contacts of these relays and through conductor 27 so as to energize and thereby open the solenoid valve 7.

A temperature-dependent resistance 10 is provided as the hot conductor associated with container 1. This temperature-dependent resistance changes its resistance when it is surrounded by liquid SF₆ instead of SF₆ gas. This is because the dissipation of heat in the case of gaseous SF₆. It is therefore necessary to install the hot conductor at the lowest point in the storage container 1, which directly actuates the relay 17 via a contact. It is also feasible to provide inside the container a light path which utilizes the physical fact that the refractive index and the light transmissivity of SF₆ gas and SF₆ liquid are different thereby to sense the difference therebetween.

A temperature-dependent resistance 10 is provided as the hot conductor associated with container 1. This temperature-dependent resistance changes its resistance when it is surrounded by liquid SF₆ instead of SF₆ gas. This is because the dissipation of heat in the case of gaseous SF₆ is less than the dissipation of heat in the case of liquid SF₆. It is therefore necessary to install the hot conductor at the lowest point in the storage container 1.

Advantageously, it is now possible, as shown in FIG. 2 to provide at the lowest point in the inner wall a blind hole 20 into which the hot conductor is inserted. For this purpose a bore is made directly into the blind hole from the outside, the hot conductor rests in this bore and extends into the blind hole. The leads are brought out through the aperture 21. To seal the container a threaded plug 22 is screwed in.

Instead of a resistance bridge it is naturally also possible to provide a condenser bridge; particularly since the dielectric constant ϵ of liquid SF₆ differs from the dielectric constant ϵ of gaseous SF₆. For this reason the sensing condenser which is located inside the SF₆ container at its lowest point is designed as a plate condenser so that its capacitance which depends upon the dielectric constant will change dependent upon whether the SF₆ between the condenser plates is in a liquid or gaseous state. FIG. 3 illustrates the use of a capacitance bridge circuit 29 from which it will be seen that plate condenser 30 is located in the same position as hot conductor 10 in the FIG. 1 bridge circuit whereas condensers 31, 32, and 33 in the capacitance bridge correspond to resistors 11, 12 and 13 of the resistance bridge circuit of FIG. 1.

However, it is also possible to provide other arrange-

ments; in particular it is possible to fit a float into the container 1 which directly actuates the relay 17 via a contact. It is also feasible to provide inside the container a light path which utilizes the physical fact that the refractive index and the light transmissivity of SF₆ gas and SF₆ liquid are different thereby to sense the difference therebetween.

I claim:

1. A gas supply plant particularly for use in supplying an insulating gaseous medium such as SF₆ to a switching installation insulated with the gas comprising a storage container receiving the gas in a pressurized state from a compressor drawing gas from the low pressure side of the switching installation and adapted to deliver the gas to the high pressure side of the switching installation, a heated ancillary pressurized gas container connected to said storage container by a pipe line including a control valve therein, a pressure gauge connected with said storage container for monitoring the gas pressure therein and which delivers a first control signal when the gas pressure falls to a predetermined level, a state measuring member located at the lowest part of said storage container and which is responsive to changes in the physical state of the medium therein from its gaseous state to its liquid state to produce a corresponding second control signal, and control means actuated by said first and second control signals acting conjointly to control the opening and closing operations of said control valve in said pipe line interconnecting said ancillary container to said storage container.

2. A gas supply plant as defined in claim 1, wherein said state measuring member located at the lowest part of said storage container and which responds to a change in physical state of the insulating medium therein is constituted by a hot conductor.

3. A gas supply plant as defined in claim 2 wherein said hot conductor forms the measuring branch of an electrical resistance bridge circuit.

4. A gas supply plant as defined in claim 1 wherein said state measuring member located at the lowest part of said storage container and which responds to a change in physical state of the insulating medium therein is constituted by an electrical condenser of the plate type.

5. A gas supply plant as defined in claim 4 wherein said plate condenser forms the measuring branch of an electrical capacitance measuring bridge.

6. A gas supply plant as defined in claim 1 wherein the lowest part of said storage container is provided with a blind hole in which said state measuring member is located.

7. A gas supply plant as defined in claim 1 wherein said control valve is of the solenoid type and is connected to an energizing source through contacts of two relays arranged in series, said relays being controlled respectively by said first and second control signals.
